UNITED STATES PATENT OFFICE.

HERBERT L. JOHNSTON, OF TROY, OHIO, ASSIGNOR TO THE HOBART ELECTRIC MANUFACTURING COMPANY, OF TROY, OHIO, A CORPORATION OF OHIO.

GEARING.

1,088,076.

Specification of Letters Patent.

Patented Feb. 24, 1914.

Application filed May 4, 1911. Serial No. 625,013.

To all whom it may concern:

Be it known that I, HERBERT L. JOHNSTON, a citizen of the United States, and a resident of the city of Troy, in the county 5 of Miami and State of Ohio, have invented certain new and useful Improvements in Gearing, of which the following is a full, clear, and exact description, reference being had to the accompanying drawings, forming 10 a part of this specification.

My invention relates to meat cutters, coffee mills, grinding machines and the like, and the primary object of the invention is to so design the construction that the machine may be driven directly by a small internal combustion engine with the casing and driving shaft of the engine directly connected with the driving shaft and casing of the machine to be driven, so that the two 15 machines may form a single machine which can be moved from place to place as desired, and in which the casing of the driving engine is so constructed and arranged, that the driven machine may be readily and 20 easily disconnected for cleaning or otherwise, and other machines for analogous purposes may be at will substituted therefor.

My invention consists in its essentials of a suitable base, upon which the driving motor 25 is supported with the machine to be driven thereby also supported on the base either directly, or as a part of the motor casing, with direct gearing connection between the driving shafts of the two machines and the necessary friction clutch intermediate the driving 30 and the driven machine, whereby the operation of the driven machine may be stopped without stopping the driving engine and whereby the engine may be started without the load. With this construction, the entire driving power is self contained in the apparatus, and no connection of any kind is required with any extraneous source of power. The various constructions of grinding 35 and chopping machines may in this way be mechanically operated by power whenever desired without reference to any fixed power supply, and the self contained machine as a whole may be moved from place 40 to place as the necessities of the location or other requirement may demand.

In the drawings, Figure 1 is a side elevation of my improved machine, partly in vertical section. Fig. 2 is a transverse section

of the driving mechanism taken on the lines 55 2, 2, of Fig. 1.

The supporting metal base for the apparatus is indicated by 1, and this base is divided into suitable compartments for holding the fuel and other necessary liquids for 60 operating the engine. As illustrated for the preferred construction, 2 indicates the chamber for the liquid fuel; 3 the chamber for the lubricating oil, and 4 the chamber for the water jacket for the engine cylinder. 65

The driving engine may be of any convenient construction of internal combustion engine, but I prefer the small vertical type two-cycle engine, in which 5 indicates the crank case; 6 the engine cylinder with water 70 jacket compartment 7; 8 is the piston with piston rod 9 coupled to the crank shaft 10, which is mounted in suitable bearings in the crank case, and is provided at one end with the fly wheel 11. At the opposite end, the 75 crank shaft 10 projects into the gear casing 12, and in this casing the pinion 13 is keyed to the crank shaft. The governor for the engine is indicated at 14, while 15 indicates the timer with handle 16 for controlling the 80 ignition. The governor is mounted on the vertical shaft 17 upon which is secured a spiral gear indicated at 18, which is driven by a similar gear mounted on the crank shaft 10, so that the governor shaft is driven 85 in proper timed relation with the engine shaft. On the lower end of this shaft connection is made with three pumps 19, 20 and 21, for feeding and circulating the water for the water jacket, lubricating oil and the fuel. 90 The details of the construction of these various parts of the engine are not illustrated for the reason that they are of the ordinary and usual construction and form no part 95 of the present invention.

The gear casing 12 is provided with a hub 22, projecting laterally which furnishes a socket for the reception of the hub 23 projecting from the casing 24 of the meat cutter, which is of the ordinary and usual construction, provided with a forcing conveyer 25, which is formed with the shaft 26, having its bearing in the hub 23 of the meat cutter casing. The outer end of this shaft 26 is provided with a tongue 27 which engages within a slot in the outer end of a sleeve 28 upon which is loosely mounted the gear 29 which meshes with the pinion 13 on 100 105

the crank shaft. Keyed on this sleeve 28 is a collar 30, and mounted on this collar 30, inside of the flange or rim of the gear 29, is a split ring 31. This split ring is expanded 5 by a beveled pin 32, which projects with its beveled edge between the open portions of the ring, and is actuated by the pin 33 carried by the grooved collar 34 which is supported by the actuating lever 35 pivoted at 10 36 to the gear casing. By shifting the actuating lever, the split ring 31 is expanded to frictionally connect the gear 29 with the sleeve 28 for driving the forcing conveyer of the meat cutter. This friction clutch 15 connection serves a very useful purpose, in that the operation of the cutter may be discontinued without stopping the engine, and further that it facilitates starting the engine, as the engine can be started when disconnected from the load.

The hub 23 on the casing of the meat cutter is held in position in the socket on the gear casing of the machine by the thumb-screw 37.

It will be evident from the foregoing description that the meat cutter can be removed at a moment's notice for cleaning, or for placing in a refrigerator, to avoid cleaning after each operation, by releasing the 30 thumb screw 37.

For the purpose of utilizing the engine for driving other machines for analogous purposes such as coffee mills, grinders and the like, the machine will be formed with a 35 hub portion to fit within the socket in the gear casing and with a driving shaft provided with a tongue to couple same to the sleeve 28 on the gear casing.

I am aware that it is old to provide an 40 electric motor with a gear casing for attaching meat cutters and analogous machines thereto, so that such machines may be directly driven by the motor. With such machine, however, the operation of the motor 45 is dependent on the electric supply, and I

know of no case where machines for grinding, meat cutting and the like have been driven by a self contained internal combustion engine, so that the apparatus can be moved from place to place, and used without regard to any fixed source of supply for the power.

Having thus described my invention, what I claim as new and desire to secure by Letters Patent, is:—

1. In combination with a driving shaft, a support therefor, a shaft to be driven thereby, a support for the driven shaft, a clutch member, driving connection between the clutch member and the driving shaft, means 60 to detachably connect said clutch to the driven shaft, and means to detachably secure the support for the driven shaft to the support for the driving shaft.

2. In combination with a driving shaft, a support therefor, a shaft to be driven thereby, a support for the driven shaft, a clutch member, driving connection between the clutch member and the driving shaft, a support for the clutch member mounted on the 70 driving shaft support, means for detachably connecting said clutch member to the driven shaft, and means for detachably securing the support for the driven shaft to the driving shaft support.

3. In combination with a driving shaft, a support therefor, a shaft to be driven thereby, a support for the driven shaft, a clutch member, means in the support for the driving shaft for mounting the clutch member, a 80 sleeve at one end thereof to receive a sleeve on the support for the shaft to be driven, detachable means for securing said sleeves together, and detachable connection between the driven shaft and the clutch member.

HERBERT L. JOHNSTON.
